VALVE ATTACHING DEVICE FOR LIQUID DISPENSERS

John A. Hopwood, Westfield, N. J., assignor to
Monitor Process Corporation, Jersey City, N. J.,
a corporation of New Jersey

Application July 7, 1945, Serial No. 603,678

1 Claim. (Cl. 153—21)

1

United States Patent No. 2,186,083, issued January 9, 1940, to Monitor Process Corporation, as assignee of William Tamminga, discloses a liquid dispenser especially adapted to dispense milk from a side delivery can. The can is provided near its base with a dispensing tube which operates through the side wall thereof and the flow of milk through this tube is controlled by a slide valve. The tube and its valve form an inherent part of the can assembly. In practice the can is filled at the creamery or other source of bulk milk supply and shipped, with all parts thereof in thoroughly sterile and uncontaminated condition, to the retailer who attaches to the valve appropriate operating means whereby milk may be dispensed into a drinking glass or other receptacle as and when desired.

It is of course essential in a can assembly of this kind, that the slide valve be locked in the tube during shipment, so that it will not inadvertently release milk from the can. The Tamminga patent referred to discloses a satisfactory arrangement for accomplishing this result. In the structure there shown, the outer end of the delivery tube is flared so as to provide an external flange. The slide valve is fitted into the outer end of the tube and comprises a metal clip provided with oppositely projecting bendable tongues. When the can is filled for shipment at the creamery these tongues are bent over the flange of the delivery tube and serve to lock the valve firmly in the outer end of the tube until the retailer receives the can and is ready to hook up the valve to appropriate valve operating mechanism.

In the past the attachment of the bendable tongues of the slide valve clip to the flange of the delivery tube has been accomplished manually, by bending these tongues in such a way as to engage the flange and lock the valve in position. The manual operation, however, has proved very unsatisfactory for many reasons. It is a slow process and requires some little skill to do it properly. Moreover it is almost impossible to uniformly bend these tongues by hand and a fair degree of uniformity is required so that the tongues may be subsequently released from the flange of the tube by disengaging means forming a part of the valve operating means. The present invention provides a very satisfactory device whereby the bendable tongues of a slide valve clip, such as described, may be readily bent at the creamery or other source of bulk milk supply when preparing the can for shipment. The device is such as to produce uniform bending in a simple and expeditious manner, so as to leave these bendable tongues in the proper condition for release by the releasing devices of the dispensing apparatus when the can has been delivered and is being set up to dispense milk. The device of this invention requires no particular skill to operate it and a uniform result is assured.

Speaking generally, the device of this invention comprises an appropriate base on which are mounted a pair of relatively movable bending jaws. One of these jaws may be fixed and the other movable and the relative movement between them is accomplished by means of an appropriate handle affording sufficient leverage to permit of the bending operation to be performed without undue labor on the part of the operator. When the jaws are retracted, a delivery tube, with a slide valve positioned in its outer end, is adapted to be placed between them, a guide being provided to insure proper placement. The jaws are then forced together and are so shaped that they engage with and bend the tongues of the slide valve clip into position to firmly seat the slide valve in the outer end of the tube and temporarily lock it in this position, so as to eliminate the slightest chance of leakage. An appropriate stop is preferably provided so as to limit the bending movement of the jaws to a predetermined spacing so as to insure uniformity of results.

30. Features of the invention, other than those adverted to, will be apparent from the hereinafter detailed description and appended claim, when read in conjunction with the accompanying drawing.

35. The accompanying drawing illustrates one practical embodiment of the invention, but the construction therein shown is to be understood as illustrative only, and not as defining the limits of the invention.

40. Figure 1 is a perspective view of a device embodying the present invention with its cover plate removed and spaced from the base of the device so as to more clearly show the underlying structure.

45. Figure 2 is a central vertical longitudinal section through the device with the parts in the positions which they occupy in the course of bending the tongues to final position.

50. Figure 3 is a plan view of the base of the device with all movable parts removed therefrom.

55. Figure 4 is a view, partly in elevation and partly in section, of the milk delivery tube with attached slide valve, the full line positions of the tongues being those occupied prior to bending and the

dotted line position showing the finally bent positions of these tongues.

Referring to the drawings, 1 indicates the base of the device. It is conveniently in the form of a casting although it may be fabricated in any other manner. In any event, it is provided with a longitudinal guide channel 2 in which are positioned two slides 3 and 4 which respectively carry upstanding bending jaws 5 and 6, the opposing faces 7 and 8 of which are shaped to cooperate with the tongues to be bent. To insure alignment between the slides 3 and 4 at all times, the slide 3 carries a fixed centering pin 9 which slidably extends into a hole 10 in the slide 4, as shown best in Fig. 2. The slides are maintained in the channel 2 by means of a cover plate 11 resting on top of the base 1 and firmly fixed thereto by means of screws 12. The center of the plate is cut away, as shown at 13, so that the jaws 5 and 6 may project upwardly therethrough and in practice the rear edge 14 of the opening 13 forms an attachment against which the back of the jaw 5 engages in a relatively fixed manner, only the jaw 6 being movable in the construction shown.

Between the jaws the respective slides are provided with raised platforms 15, substantially flush with the upper surface of the plate 11 and back of these platforms the plate 11 has attached thereto a strip of metal, the front edge 16 of which forms an abutment to properly position the valve for coaction with the jaws. An operating handle 17 is pivoted to the base 1 by means of a screw and is connected by a link 19 to the slide 4. This handle is relatively long so as to give sufficient leverage to permit of operation of the jaw 6 with considerable force through the application of relatively little manual energy.

In Figures 2 and 3 is shown a milk delivery tube 20, the outer end of which is provided with an external flange 21. The metal clip 22 of the slide valve projects into the outer end of the tube and has at its outer end an annular flange 23 provided with oppositely projecting bendable tongues 24.

In utilizing the present invention with a structure of this kind the slide valve is manually inserted into the outer end of the tube and the parts as thus assembled are then placed in upright position upon the platform 15 with the back edge of the flange engaging the stop 16. The handle 17 is then operated in a clockwise direction to force the jaw 6 toward the jaw 5 and the shaping of the jaws is such as to cause the tongues to be bent inwardly over the flange 21 of the tube, so as to draw the flange 21 tightly down against the flange 23 and clamp these parts firmly together. When this has been accomplished the tongues will have partaken of the position shown in dotted lines of Fig. 4 where they will remain to hold the parts in proper assembled relation until subsequently released in the manner stated. To preclude overbending of these tongues an appropriate stop is provided to limit the bending operation and while this stop may partake of various

forms, it is shown in the drawings as embodying an adjustable stop 25 adapted to be locked in adjusted position by means of screws 26 and so arranged as to be engaged by the handle 17 when the tongues have been bent as much as desired and necessary.

After the bending operation has been completed, the handle is swung to the right in Fig. 1, to release the delivery tube and prepare the device for operation upon the next tube. To hold the device in place while it is being operated, the base 1 is preferable provided with holes 27 for attaching the device to a bench or table.

Experience with the structure hereinbefore described has shown it is capable of assembling valves and outlet tubes at a greater speed and with much more uniformity than could possibly be accomplished by hand and its use insures the proper functioning of the valve releasing devices of the dispensing means with which the tubes hereinbefore referred to are adapted to cooperate.

The foregoing detailed description sets forth the invention in its preferred practical form, but the invention is to be understood as fully commensurate with the appended claim.

Having thus fully described the invention, what I claim as new and desire to secure by Letters Patent is:

A device for attaching a slide valve provided with bendable tongues to a delivery tube having a flanged outer end comprising: a base provided with a guide channel, a cover plate positioned on the base and provided with an opening registering with a portion of the length of the guide channel, two bending jaws supported on the base and one slidably in the channel, each of said jaws having a platform, the upper face of which is flush with the top of said cover plate and from the opposite ends of which platforms the bending jaws project upwardly and toward one another to permit the slide valve to rest upon said platforms and the flush upper surface of said cover plate, a positioning abutment carried by the cover plate to insure accurate positioning of the slide valve between said jaws, a lever for imparting relative movement to the jaws to bend the tongues of the slide valve to engage with and clamp the flange of a tube associated with said valve, and a stop for limiting the movement of the jaws toward one another to insure uniformity in such bending operations and to preclude crushing of the tube.
